US00D855579S

(12) **United States Design Patent** (10) **Patent No.:** **US D855,579 S**
Clark et al. (45) **Date of Patent:** **** Aug. 6, 2019**

- (54) **EAR CUP COUPLER FOR AN OVER EAR HEADPHONE**
- (71) Applicant: **MrSpeakers, LLC**, San Diego, CA (US)
- (72) Inventors: **Daniel William Clark**, San Diego, CA (US); **Robert Jason Egger**, San Diego, CA (US)
- (73) Assignee: **MrSpeakers, LLC**, San Diego, CA (US)
- (**) Term: **15 Years**
- (21) Appl. No.: **29/619,808**
- (22) Filed: **Oct. 2, 2017**
- (51) LOC (12) Cl. **14-01**
- (52) U.S. Cl. **USPC D14/205**
- (58) **Field of Classification Search**
USPC D14/205, 223, 248, 249, 250, 253; D29/112; 2/209; 181/129, 130, 135; 379/430, 431; 381/380, 381, 374, 74; 455/90.3, 575.1, 569.1; D13/133
CPC H04R 1/1066; H04R 1/1016; H04R 5/033; H04R 5/0335; H04R 25/00; H04R 1/10

(57) **CLAIM**

The ornamental design for an ear cup coupler for an over ear headphone, as shown and described.

DESCRIPTION

FIG. 1 is a first side view of the design.

FIG. 2 is a second side view of the design of FIG. 1.

FIG. 3 is a third side view of the design of FIG. 1.

FIG. 4 is a rear view of the design of FIG. 1.

FIG. 5 is a front view of the design of FIG. 1.

FIG. 6 is a top view of the design of FIG. 1; and, FIG. 7 is a perspective side view of the design of FIG. 1. The broken lines depict environment that forms no part of the claimed design.

1 Claim, 4 Drawing Sheets
